UNITED STATES PATENT OFFICE.

ARTHUR A. MCGILL, OF WISNER, NEBRASKA.

PLIERS.

Application filed February 3, 1927. Serial No. 165,637.

This invention relates to improvements in the construction of pliers.

Briefly, the invention has reference to a tool of this class wherein a novel double fulcrum means is provided for producing a powerful leverage, finer adjustment of the gripping jaws, and substantially parallel relationship in the final movement of the jaws, to adapt them for engaging flat sided objects, such as nuts, bolt heads, and the like.

More in detail, the invention has reference to a structure of this class which includes a primary fulcrum which is located in inwardly spaced relation to the gripping surfaces of the jaws, and a secondary fulcrum which is initially ineffective and located adjacent the gripping surfaces for producing powerful leverage and a tenacious grip on the object.

An important feature of the invention beyond the employment of the successive double fulcrum action is an adjustable carrier for the secondary fulcrum, the carrier being movable at a predetermined time, then becoming automatically set and serving to hold the secondary fulcrum stationary, while the movable jaw pivots about it to bring it into substantially parallelism with the stationary jaw, and to produce the efficient grip.

The configuration of the parts, as well as their intimate association and relation, will become more readily apparent from the succeeding detailed description.

In the drawings:—

Figure 1 is a side elevation of pliers constructed in accordance with the invention showing the jaws open and the secondary fulcrum carrier in released position.

Fig. 2 is a longitudinal section taken approximately upon the plane on the line 2—2 of Fig. 1, looking in the direction of the arrow,

Fig. 3 is a fragmentary perspective view of the movable jaw,

Fig. 4 is a perspective view of the secondary fulcrum carrier.

Considering now the drawings in detail, it will be seen that the reference character 1 designates one handle or lever which carries the stationary gripping jaw 2. It will be noted that the portion of the material joining this jaw with the handle is formed somewhat as a segment of a circle, this por-

tion being represented at 3. Also, this portion has a sector 4 cut out therefrom, and the outer arcuate edge of this sector is provided with ratchet teeth 5 disposed on an arc of a predetermined curvature. The curved edge 6 of the segment 3 is also of arcuate formation and the arc is that of a circle greater than the circle upon which the toothed arc 5 is based.

Attention is now invited to Fig. 3 wherein the movable jaw member, shown at 7, is represented. Here the reference character 8 designates the complementary lever or handle, 9 the relatively movable jaw for cooperation with the jaw 2, and 10 the webs which join this jaw with the handle 8. These webs are disposed in spaced parallelism to each other, and are so spaced as to permit them to straddle the segmental portion 3.

The lower arcuate edges are formed with notches 11 providing seats for reception of the primary fulcrum pin 12, rigidly mounted on the handle 1 at the juncture of the latter and said segmental portion. It will be noted that one side of the notch is substantially hooked in formation, while the other side is of inclined form to operate as a cam in a manner to be hereinafter made plain.

The secondary fulcrum carrier is represented generally by the reference character 13, and this comprises a pair of spaced parallel side plates 14 of somewhat triangular form, the same being provided at their apices with elongated slots 15. Rigidly or otherwise firmly fastened between the outer wide ends is a toothed block 16, the teeth of which are adapted to cooperate with the aforesaid teeth 5.

In an opposite corner, are holes 17 cooperating with holes 18 in the webs 10 to accommodate the secondary fulcrum pintles 19. It will be noticed from Fig. 2, that there are two of these pintles. They are however, referred to, as a unit, by the expression secondary fulcrum.

It will be noted that the side plates of the carrier 13 are interposed between the wings or webs 10 and the aforesaid segment 3. Also the block 16 is located in the open sector 4. In addition, a coiled spring 20 is connected with this block and the main fulcrum pin 12, as shown better in Fig. 2.

It is obvious from the foregoing description, that when the parts are assembled as shown in Fig. 1, and the handle 8 is grasped

and moved toward the handle 1, the movable jaw structure 7 as well as the carrier 13 will move, as a unit, upon the primary or main fulcrum pin 12, in order to obtain the initial adjustment of the jaws. However, as soon as the movable jaw comes into engagement with the object to be gripped, a resistance is set up, causing the cam edges of the aforesaid notches 11 to ride outwardly or upwardly upon the fulcrum pin 12.

This bodily movement naturally moves the carrier 14 outwardly until the teeth on the block 16 engage the teeth 5, thus temporarily holding the carrier 13 against further swinging movement. A further movement of the handle 8, thereby brings the secondary fulcrum 19 into play, whereupon the power is transmitted from this fulcrum, which being close to the gripping surface of the jaw, increases the leverage, and permits a more sturdy grip to be had.

With this arrangement, it is obvious that the additional movement of the jaw 9, upon the secondary fulcrum pins 19 allows the jaws to come more nearly into parallelism, thus adapting them for gripping flat sided objects as before explained. Of course, when the parts are moved in a reverse manner the spring 20 retracts the carrier and allows the parts to resume initial position.

Undoubtedly by considering the description in connection with the drawings, a clear understanding of the invention as to construction and arrangement of parts, as well as the advantages and operation will be had.

In view of this, a more lengthy description is deemed unnecessary.

Minor changes coming within the field of invention claimed, may be resorted to if desired.

Having thus described my invention, what I claim as new is:

1. In a tool of the class described, pliers comprising a relatively stationary jaw member embodying a jaw and an operating handle therefor, a main fulcrum pin carried by said handle, a relatively movable jaw member embodying a jaw, an operating handle for said last named jaw pivotally and movably mounted on said main fulcrum pin, and means interposed between the movable and stationary jaw members and provided with a secondary and successively operable fulcrum upon which the movable jaw is also mounted.

2. In a structure of the class described, pliers comprising a stationary jaw member embodying a jaw and an operating handle therefor, a main fulcrum pin carried by said handle, a movable jaw member including a jaw for cooperation with said first-named jaw, an operating handle for the movable

jaw, the movable jaw and its handle being pivotally and shiftably mounted upon the main fulcrum pin, a carrier interposed between said jaw members and handles, and a secondary fulcrum carried by said carrier, said movable jaw member being connected with said secondary fulcrum.

3. Pliers comprising a stationary jaw member having a jaw and an operating handle therefor connected to said jaw through the medium of a relatively wide segment, a main fulcrum pin at the juncture of said segment and handle, a relatively movable jaw member including a jaw, an operating handle for said last-named jaw, webs joining the latter jaw with its handle, said webs straddling said segment and being provided with notches forming seats for reception of the fulcrum pin.

4. Pliers comprising a stationary jaw member having a jaw and an operating handle therefor connected to said jaw through the medium of a relatively wide segment, a main fulcrum pin at the juncture of said segment and handle, a relatively movable jaw member including a jaw, an operating handle for said last-named jaw, webs joining the movable jaw with its handle, said webs straddling said segment and being provided with notches forming seats for reception of the main fulcrum pin, a secondary fulcrum, and a carrier for said secondary fulcrum including spaced parallel plates interposed between said webs and sector, said webs being rockably connected with the secondary fulcrum on said carrier.

5. In a tool of the class described, pliers comprising a relatively stationary jaw member having a jaw and an operating handle for said stationary jaw joined thereto thru the medium of a connecting segment, said segment being formed with an open sector, one edge of which is formed into an arcuate toothed rack, a relatively movable jaw member including a jaw opposed to said first jaw, an operating handle for the movable jaw, spaced parallel webs joining the movable jaw with its handle, a primary fulcrum pin located at the juncture of said segment and first named handle, said web being provided with notches receiving said fulcrum, a carrier interposed between said webs and segment and including spaced parallel plates having slots connected with said primary fulcrum, a toothed block carried by said plate and cooperable with said rack, and secondary pintles carried by said carrier and pivotally connected with said webs at a point spaced outwardly from said primary fulcrum.

In testimony whereof I affix my signature.
ARTHUR A. MCGILL.
